A. H. WRIGHT.
SEWING MACHINE SHIELD.
APPLICATION FILED SEPT. 25, 1917.

1,288,359.

Patented Dec. 17, 1918.

Inventor:

Alpha St. Wright.

By Henry J. Miller
Atty.

UNITED STATES PATENT OFFICE.

ALPHA H. WRIGHT, OF ALBANY, NEW YORK, ASSIGNOR TO FREDERICK OSANN COMPANY, A CORPORATION OF NEW YORK.

SEWING-MACHINE SHIELD.

1,288,359.

Specification of Letters Patent. Patented Dec. 17, 1918.

Application filed September 25, 1917. Serial No. 193,185.

To all whom it may concern:

Be it known that I, ALPHA H. WRIGHT, a citizen of the United States, residing at Albany, county of Albany, State of New York, have invented Improvements in Sewing-Machine Shields, of which the following is a specification, reference being had to the accompanying drawings, forming part thereof.

10 This invention has reference to improvements attached or adapted to be attached to the heads of sewing machines to protect the operator particularly the operator's eyes from flying particles of needles broken during the operation of the machine.

One object of the invention is to provide a shield of the nature described adapted to be readily attached to the head of a sewing machine to protect the operator without obstructing the operator's view of the work or his or her manipulation of parts of the work, as in sewing on buttons.

Another object of the invention is to provide a shield of the nature described which, 25 when mounted on a machine, can be swung or adjusted as desired by the operator.

Other objects of the invention will appear from the following description.

The invention consists in such novel features of construction and combination of parts as shall hereinafter be more fully described and pointed out in the claim.

Figure 1, represents a view of the improved shield attached to the head of a sewing machine of well known construction, parts of the sewing machine being omitted as they form no part of the present invention.

Fig. 2, represents a view substantially 40 at right angles with Fig. 1.

Fig. 3, represents a plan view of the improved shield.

Similar characters of reference designate corresponding parts throughout.

45 As shown in the drawings A and B represent respectively portions of the head and work plate of a sewing machine of any well known construction provided with the usual stitch forming devices including the needle

C. In order to more clearly point out the 50 advantages of the present invention I have preferred to illustrate the same in combination with a sewing machine having a button clamp or other work holder of ordinary construction, parts of which are shown at 55 D, ready access to which is desirable at all times for inspection and for adjustment of parts of the work holder or of some part of the work in said holder.

The improved shield comprises the supporting bracket 5 adapted to be secured to the head A of the sewing machine and having, pivotally connected with said bracket, the arm 6 which has the section or member 7 mounted to swing relative to the axis of 60 said arm and to be secured in the adjusted position by means of the screw nut 8. At the outer portion of member 7 is the clamp or socket 9 into which is received and retained the upper edge portion of the shield 65 10 of glass or other transparent material.

The uses of the improved shield will be apparent. In sewing machines and particularly in power driven button sewing and similar machines the stitch forming means 75 are operated at great speed and extreme nicety of adjustment of the buttons or other parts of the work is necessary in order that the needle should not strike the same and be broken. The button or button 80 holder should therefore be in view of the operator in order to avoid such breakage by adjustment of the button before the stitching operation. Notwithstanding the careful adjustment of the work and the needle 85 it is found that breakage of needles often occurs with the result that parts of the broken needles fly with considerable force toward the operator.

By the use of this device the operator's 90 face is protected from flying particles of needles or buttons without obstructing his or her view of the work and without obstructing his or her access to the work below the lower edge of the shield 10. It is also to 95 be noticed that this shield may be swung away from its normal position and can be adjusted as to its angle of inclination.

Having thus described my invention I claim as new and desire to secure by Letters Patent.

5 A shield apparatus comprising a bracket adapted to be secured to the head of a sewing machine to extend laterally thereof, an arm pivoted to said bracket to extend trans-

versely of said head, said arm having a pair of clamping plates one of which is rotatably adjustable on said arm, and a 10 glass shield having its upper edge clamped between said plates.

ALPHA H. WRIGHT.
